UNITED STATES PATENT OFFICE.

ZABBY LASSOR, OF STINESVILLE, INDIANA, ASSIGNOR OF TWO-THIRDS TO
CHARLES C. DUNN AND FRANK MOORE, OF SAME PLACE.

CHANNELING-MACHINE.

SPECIFICATION forming part of Letters Patent No. 471,797, dated March 29, 1892.

Application filed March 28, 1891. Serial No. 386,788. (No model.)

To all whom it may concern:

Be it known that I, ZABBY LASSOR, a citizen of the United States, residing in Stinesville, county of Monroe, and State of Indiana, have 5 invented certain new and useful Improvements in Stone-Channeling Machines, of which the following is a specification.

This invention relates to improvements in stone-channeling machines which travel back and forth over the stone to be channeled and produce the channel by the action of cutters arranged and secured together in gangs; but my invention, however, is more especially directed to improvements in the clamping devices for rigidly securing together the cutters of a gang. These gangs of cutters operate by gravity—that is to say, they are raised by power and dropped by gravity to strike successive blows, whereby the channel is formed, and are, therefore, necessarily quite long, very heavy, and require correspondingly ponderous clamping-plates for holding them together when in operation. The clamping-plate must not only hold the cutters, but guide them in their descent, and to this end are vertically channeled to receive fixed guide-plates or trackways directing their movement, and, besides, must be so constructed as to provide for their connection with the devices for raising the cutter-gangs in position to strike blows. As heretofore constructed, these clamps have been made in two parts, one part of which may be said to be the fixed jaw or main body of the clamp, and having cast therein the guide-channels and projecting therefrom a lug for connecting it with the lever or other device for elevating the cutters. The other part of the clamp constitutes the movable jaw thereof and is secured to the 40 sliding but otherwise fixed jaw by bolts, which have usually been passed through the movable jaw and screwed into the fixed jaw, so as to firmly clamp the gangs of cutters lying between these two jaws. In the practical operation of these machines, notwithstanding the very strong and ponderous construction of these clamps, and owing to the sudden and violent jars they are subject to when the cutters are in operation, these bolts fre-

quently break, and more frequently both the 50 fixed jaw and the movable jaw are fractured and broken at their corners, where they are the weakest, because, as will be understood, the bolts must be at a point on either side of the cutters and on a line passing through 55 the channeled portion of the fixed clamping-jaw.

The object of my invention is to provide an improved clamp which shall be simple, durable, and effective, and in which the parts are 60 so constructed and arranged as to be capable of being readily and conveniently put together or taken apart for repairs or renewal; and my invention consists in certain features of novelty in the construction, arrangement, and combination of parts hereinafter described with reference to the accompanying drawings, and more particularly pointed out in the claims.

In the said drawings, Figure 1 illustrates a 70 perspective view of so much of a stone-channeling machine as embodies my invention; Fig. 2, an inner face view of the base or back plate of the fixed but sliding jaw of my clamp; Fig. 3, a transverse section on the line 3 3 of 75 Fig. 1, with the actuating-lever shown in full lines; Fig. 4, a similar but enlarged detail view of the clamp with the cutters removed, and more particularly illustrating the bolts and position thereof for locking the movable 80 jaw of the clamp to the fixed jaw for clamping the gang of cutters; Fig. 5, a front elevation of the fixed but sliding jaw of the clamp, more particularly illustrating the arrangement of the cutters therein; Fig. 6, a trans- 85 verse section on the line 6 6 of Fig. 3.

Similar letters and numerals of reference indicate the same parts in the several figures of the drawings.

A indicates a gang of cutters of the usual 90 form and clamped together toward their upper ends by an ordinary clamp B, and bearing at these ends on the usual and ordinary face-plate C of the machines in which said cutters are designed to be employed. Upon 95 their rear sides and toward their lower ends these cutters bear and slide upon a fixed bed-plate D, rearward of which is a revolving cam

E, the purpose of which will presently be described.

The bed-plate D is bolted in the usual manner to the frame of the machine and

5 projects outwardly beyond and downwardly to within a short distance of the rails F, as shown, for the purposes of illustrating the relative position of the bed-plate and the cutters thereof, it being understood that the track 10 upon which the machine moves is a temporary track, and is usually so constructed as to be bodily laterally movable for the purpose of transferring the machine to cut a new channel; the track governing the direction as to 15 the line of the channel. The bed-plate is provided with a slot, (see Fig. 3,) through which projects a clamp G, provided on each side with channels embracing the bed-plate, which thereby forms a trackway guiding the 20 clamp G and in turn the cutters while in operation, the cutters being elevated by means of arms e e, actuated by the cam E, and by reason of one of said arms working in a rearwardly-projecting lug g of the clamp. As 25 heretofore constructed, these clamps have consisted of but two parts or casings—namely, the movable or clamping jaw and the sliding or otherwise fixed jaw—the fixed jaw having cast therein a channel embracing the slotted 30 walls of the bed-plate.

The result of casting the fixed jaw in one piece, as has already been intimated, results in the total loss of that jaw should any part of it be broken, as frequently happens, and 35 as this breakage usually occurs through its flange or lip embracing the outer side of the bed-plate it is one purpose of my invention to so construct this fixed jaw that only a portion of it is lost by such breakage, and at the same 40 time to have said jaw as rigid and durable as though cast in one piece. To these ends the fixed jaw is cast or constructed in two pieces, which for the purposes of clearness will be described as the base-plate 3 and the face-plate 2. The base-plate 3 has integral therewith the lug g, before described, and formed in its face a dovetail groove. The face-plate has formed therewith a rib or tenon conforming to the groove in the base-plate, said 45 groove and tenon preferably tapering toward one end, so that the two parts may be wedged tightly together, the face-plate having at its rear side an offset and forming the bottom and front wall of the groove or channel 50 embracing the bed-plate D, the straight edge of the base-plate forming the other wall. To promote the locking of the base and face plates of this sliding but otherwise fixed jaw of the clamp and to insure them against any 55 60 possibility of moving upon each other after being united and in their operative position, a pin 4 is projected through the base-plate and the tongue or tenon of the face-plate; but any other form of key may answer the 65 same purpose, although in any event it should

be of such a character that while securely locking the two parts together it may be removed when for any reason it is desirable to separate them.

With the fixed jaw of the clamp constructed 70 in the above-described manner it will be seen by an inspection of Fig. 3 that should the face-plate become injured it may be removed from the base-plate by raising or lowering the clamp out of one end of the slot in the 75 bed-plate, removing the pin 4, sliding the face-plate off of the base-plate, and as readily and quickly substituting a new face-plate.

In order that the movable or gripping jaw of the clamp, which is secured to the fixed 80 jaw, may be readily removed when broken and in order that the bolts usually employed for uniting the two jaws may also be readily removed when broken and new ones substituted, I employ bolts 6, (see Fig. 4,) provided 85 with screw-threads removed from their heads and next their opposite extremities or points. The face-plate of the clamp is provided with countersinks at the inner face of its flange or lip, through which the bolts pass, and thence 90 through perforations in the movable jaw, nuts 7, working on projecting ends of these bolts, serving to tighten the movable jaw on the gang of cutters confined between this jaw and the sliding jaw. By this construction and ar- 95 rangement of the bolts it is obvious that when broken the head end may be readily pushed or punched out of the sliding jaw, and that as they do not screw into the movable jaw the other ends may be as readily removed. 100 The head end of the broken bolt may be dropped or readily pushed out of the base-plate of the fixed jaw and the projecting or nut end of said bolt be readily grasped and unscrewed from the sliding jaw, if screwed 105 therein, though in practice there are preferably no screw-threads in the sliding jaw, and, as a result, this end of the bolt may likewise be dropped or easily pulled out of the sliding 110 jaw.

Having described my invention, what I claim, and desire to secure by Letters Patent, is—

1. In a stone-channeling machine, the combination, with the gangs of drills, of a clamp 115 therefor, the sliding but otherwise fixed jaw of which is composed of a face and back plate removably dovetailed together, and an actuating-arm connected with the back plate, substantially as described.

2. In a stone-channeling machine, the combination, with the gangs of drills, of a clamp therefor having a fixed jaw composed of two parts removably dovetailed together, and a pin projecting through and locking said two parts 125 against a longitudinal movement along their dovetailed connection, substantially as described.

3. In a stone-channeling machine, the combination, with the gangs of cutters and a slot- 130

ted bed-plate, of the face-plate 2, having a dovetail tenon and being provided at both ends of its rear side with offsets, the base-plate 3, overlapping said offsets, so as to form therewith channels for the reception of the edges of the bed-plate, and said base-plate having a dovetail groove in which said tenon

fits, and a removable jaw secured to said face-plate for clamping the cutters thereto, substantially as set forth.

ZABBY LASSOR.
